DIE, DIE HOLDER, AND EJECTOR

Lester Warren Nelson, Bridgeport, Conn., assignor
of one-half to Edward L. Monson, Bridgeport,
Conn.

Application June 2, 1934, Serial No. 728,710

7 Claims. (Cl. 164—33)

This invention relates to blanking and piercing dies, that is to say, to dies for stamping a flat blank from a sheet of metal and dies for punching a hole through a blank.

For the sake of definiteness in description, the term "die" will herein be used to denote the element on which the metal sheet rests, said element having an opening therethrough of the same outline as the blank to be produced, and the term "punch" will be used to denote the element which is forced against the sheet and into the die to shear from the sheet a blank having the outline of the punch and die.

The general object of the invention is to reduce the cost of the die and to obviate the necessity of providing a die set for each die.

Heretofore it has been the practice to form the die of a relatively thick piece of metal and to mount the die in a shoe having an opening therethrough to allow the blank to drop through the die and the shoe into a receptacle placed in position to receive the blank. The cost of forming an opening of the desired outline through such a heavy piece of metal is relatively great and the necessity of providing for each die a shoe adapted to support the die and allow the blank to pass through has added to the expense of tooling up for the manufacture of a given part.

The present invention aims to reduce tool expense by forming the die of a relatively thin piece of metal and by supporting the die in a universal die holder. In order to prevent the relatively thin die from springing under the pressure exerted by the punch, the die holder is so constructed as to afford full support for the die during the effective (i. e. the shearing) portion of the punch stroke. For this purpose the support for the die extends clear across the opening in the die so as to support the die up to the outline of the opening in the die. Since the support for the die thus extends across the opening in the die, there is no opening in the support through which the blank may drop when severed from the sheet. Hence, I have provided means for ejecting the blank, as will hereinafter appear.

In the accompanying drawings,

Figure 1 is a plan view of a universal die holder, die and punch embodying the features of my invention, pneumatic means being employed to eject the blank.

Fig. 2 is an elevation of said apparatus.

Fig. 3 is a section on line 3—3 of Fig. 1.

Fig. 4 is a fragmental view of the die.

Fig. 5 is a view of the blank which the particular die herein shown is adapted to produce.

Fig. 6 is a plan view of an alternative construction of my invention, wherein a mechanical or non-pneumatic ejector is employed.

Fig. 7 is an elevation of the parts shown in Fig. 6.

Fig. 8 is a fragmental sectional view illustrating the ejector.

Fig. 9 is a fragmental plan view of the ejecting mechanism.

Merely for the sake of clearness of understanding, I have shown in Fig. 5 a blank A which the particular die shown in Figs. 1 and 2 is adapted to produce, although it will, of course, be understood that blanks of a great variety of outline may be made by means of dies embodying the present invention.

The die 1 has an opening 2 therethrough which is of the outline of the blank A. The punch 3 has an exterior form corresponding to the form of the blank. The punch 3 is attached to a punch holder 4 adapted to be operated by the ram of a punch press, the punch holder being guided in any usual or desired manner for accurate movement toward and away from the die holder 5. The die holder is adapted to be secured in the ordinary or any preferred manner to the bed of the punch press.

The die 1 may be of any suitable external form, being herein shown as oblong in form. In order that the die holder shall be capable of use with various dies I contemplate that the dies shall all be of the same external form and dimensions.

The die holder 5 comprises a shoe 6 having a recess therein of the same width and length as the standardized die 1, said recess being indicated at 7 in Fig. 3. The recess 7 is of sufficient depth to receive not only the die 1 but also a rest block 8, said rest block being of approximately the same width and length as the standardized die. The upper surface of the rest block 8 is accurately ground so as to provide a good seat for the die. The rest block has no perforation therein corresponding to the opening 2 of the die, but, on the contrary, extends clear across said opening so as to afford perfect support for the walls of the opening 2.

The walls of the opening 2 are tapered at an angle of about one degree so as to provide clearance between the blank and the lower portion of said wall, so that when the punch descends through the sheet the blank shall drop onto the rest block 8 by its own weight.

In order to provide space through which the blank may be ejected, I provide means for sup-

porting the die 1 in such a manner that it shall rest solidly upon the rest block 8 while the blank is being sheared out of the sheet and shall be elevated above the rest block 8 after the blank 5 has been produced so as to provide space between the die and the rest block through which the blank may be ejected.

The die 1 is mounted for vertical movement on four guide studs 9 fixed in the shoe 6, said studs 10 extending through openings 10 (Fig. 4) in bronze bushings 11. These bushings are pressed into holes broached in the die. The openings 10 are drilled with the aid of a drill jig after the die 15 has been hardened in order to insure that there shall be no misalignment between the die and the punch.

Four studs 12 are guided for vertical movement in openings in the shoe 6 and the rest block 8, said studs being supported upon and normally urged upward by expansive springs 13. The studs 12 support two parallel bars 14 which lie in slots formed in the rest block 8 and which underlie the die 1. When the punch 3 is forced against a sheet of metal lying upon the die 1, 25 the die is forced downwardly into contact with the rest block 8 against the pressure of the springs 13, but as soon as the blank has been severed from the sheet the springs 13 raise the die 1 into the normal position shown in Fig. 3, 30 thus providing a space between the die 1 and the rest block 8 through which the blank may be ejected.

The means shown in Figs. 1 and 2 for ejecting the blank utilizes compressed air to blow the blank horizontally out from under the die. Compressed air is supplied from any suitable source and is controlled by a valve (not shown) arranged to be automatically operated in the 35 operation of the punch press, said valve releasing a predetermined amount of compressed air when the press ram is traveling upwardly. In Fig. 1, 15 is a tube connected to said valve to conduct compressed air to a duct 16 in the die holder, said duct in turn communicating with a 40 duct 17. The duct 17 is connected to the recess 18 opposite the space normally provided between the die 1 and the rest block 8 by means of ports 19. These ports are controlled by means of adjustable spring pressed valves 19. The valves 19 45 provide means for adjusting the flow of air through the ports 18 in accordance with the shape of the blank so that the blank shall not become wedged between the bars 14, but shall be blown out through the space between said 50 bars.

20 (Fig. 3) denotes a stop on the die for the purpose of locating the end of the sheet in proper relation to the opening 2. 21 is a stripper of any desired type. 60 In Figs. 6 to 9 I have shown an alternative form of ejector mechanism comprising an ejector slide 22 which is arranged to be reciprocated in the space between the die 1 and the rest block 8. The ejector slide 22 is connected by means of 65 a rivet 23 to a rack 24. Said rack meshes with a pinion 25 which is fixed to the lower end of a pin or shaft 26. The upper portion of the shaft 26 extends within a bushing or sleeve 27 which is secured to the punch holder 4a. In order to 70 cause the shaft 26 to turn as the punch holder 4a is reciprocated, I provide a connection between said parts comprising two bearing balls 28 mounted in recesses in the bushing 27 and extending into spiral grooves 29 in the shaft 26. 75 As the punch holder 4a is reciprocated, the shaft

26 will be revolved to reciprocate the ejector slide 22.

By reference to Fig. 8, it will be noted that the forward end 30 of the ejector slide 22 is turned upwardly and that the forward end of the slide 5 retainer cover 31 is beveled, thus providing a space 32 between the front end of the ejector slide and the front end of the slide cover plate. In piercing operations a small slug may drop after the ejector has been advanced across the 10 die plate, and if this occurs the slug will be received in the space 32 on the ejector slide and will be withdrawn from between the die and the rest block as the ejector slide returns to the normal position shown in Fig. 8, thus insuring that 15 there shall be nothing between the die and the rest block when the die is again forced down.

It will be evident that by making the dies to standard outside dimensions, the die holder herein shown may be used for any number of dies. 20 The dies may be made of relatively thin stock, as for example, three-eighths of an inch thick, and thus may be produced much more economically than has been possible in the prior art. Notwithstanding the thinness of the die, it may be 25 used in the production of blanks from relatively heavy stock, since the die rests firmly upon a substantial flat element, namely, the rest block 8.

While the drawings show a blanking die, it will be apparent that the invention is capable of use 30 in connection with piercing dies and blank pierce follow dies.

One of the advantages of the present construction is that a change from one die to another may be made in a relatively short time, since the die 35 1 and the punch 3 may be quickly removed and another pair substituted without any adjustment of the die holder or the punch holder.

While I have described the construction herein shown with considerable particularity, it will be 40 understood that the invention is not limited to the details set forth, but that, on the contrary, various changes may be made within the scope of the appended claims.

I claim as my invention:

1. In a die mechanism, a supporting element, a die having an opening therethrough, the shape of which opening determines the outline of the blank to be formed, a reciprocating punch, a rest block for supporting the die at the walls of said 50 opening during the effective portion of the stroke of the punch, means for normally supporting the die at a distance above the rest block to provide a laterally-extending space between the die and the rest block through which the blank produced 55 by the punch and die may be laterally removed, said means yielding under the pressure exerted upon the die by the punch to allow the die to descend into contact with the rest block, and means for accurately guiding the die in its movements 60 toward and away from the rest block.

2. In a die mechanism, the combination of a supporting element having a recess therein, a relatively thin die of standardized external form in said recess, said die having an opening there- 65 through to receive a cooperating punch element, a rest block in said recess below the die, means for normally supporting the die at a distance above the rest block, said means yielding under the pressure exerted upon the die in the punching operation to allow the die to descend to contact with the rest block for the effective portion of a punch stroke, said supporting means comprising two parallel bars extending in slots in the rest block and underlying the die, and springs 75

underlying the bars and tending to raise the latter, and means for ejecting a blank horizontally out through the space between the die and the rest block.

5. 3. In a die mechanism, the combination of a die having an opening therethrough to receive a cooperating punch element, a rest block below the die, means for normally supporting the die at a distance above the rest block, said means yielding under the pressure exerted upon the die in the punching operation to allow the die to descend to contact with the rest block for the effective portion of a punch stroke, and means for ejecting a blank through the space between the die and the rest block, said ejecting means comprising an ejector slide arranged to be reciprocated in the space between the slide and the rest block.
4. In a die and die-holder, the combination, 20 with a universal supporting element having a recess of standardized form and size to receive interchangeable relatively thin die-plates of standardized external form and size corresponding to said recess, of such a die located in said recess and having a die opening therethrough, the shape 25 of which opening determines the outline of the blank that is to be sheared from a sheet by a cooperating punch element, a rest block in said recess below the die for supporting the die at the walls of said opening, and means for normally supporting the die at a distance above the rest block to provide a laterally extending space between the die and the rest block through which the blank may be laterally removed, said means 30 yielding under the pressure exerted upon the die by the punch element in operation to allow the die to bear against the rest block during the shearing operation.
5. In a die mechanism, the combination of a 35 die, a coacting reciprocatory punch, a rest block below the die, means for normally supporting the die at a distance above the rest block, said means yielding under the pressure exerted upon the die

in the downward stroke of the punch to allow the die to descend and bear against the rest block during the effective portion of the downward stroke, and means operating in timed relation with the upward stroke of the punch for laterally ejecting the blank through the space between the die and the rest block.

6. In a die mechanism, the combination of a relatively thin die having an opening therethrough the shape of which opening determines the outline of the blank to be formed by a cooperating punch element, a rest block below the die for supporting the die at the walls of said opening during the effective portion of the punch stroke, and means for normally supporting the die at a distance above the rest block to provide a laterally-extending space between the die and the rest block through which the blank produced by the die may be laterally removed, said means yielding under the pressure exerted upon the die 20 in operation to allow the die to approach the rest block during the preliminary portion of the punch stroke and to bear against the rest block during the effective portion of the punch stroke.

7. In a die mechanism, the combination of a die 25 having an opening therethrough the shape of which opening determines the outline of the blank to be formed by a cooperating punch element, said die having a plane lower side, a rest block below the die, for supporting the die at the walls 30 of said opening in the punching operation, said rest block having a plane upper side against which the plane lower side of the die bears during the effective portion of the punching operation, means for normally supporting the die at a distance above the rest block, the die in the punching operation descending to contact with the rest block for the effective portion of a punch stroke, and means for ejecting a blank through the space 35 normally provided between the die and the rest block.

LESTER WARREN NELSON.
